UNITED STATES PATENT OFFICE

129,256

DESIGN FOR A DOLL HEAD OR SIMILAR ARTICLE

Edgar Bergen, Beverly Hills, Calif.

Application October 26, 1940, Serial No. 96,100

Term of patent 14 years

To all whom it may concern:

Be it known that I, Edgar Bergen, a citizen of the United States, residing in Beverly Hills, California, have invented a new, original, and ornamental Design for a Doll Head or Similar Article, of which the following is a specification, reference being had to the accompanying drawing, forming a part thereof in which:

Fig. 1 is a front view of the doll head or similar article showing my new design;

Fig. 2 is a profile view of the doll head or similar article from one side; and

Fig. 3 is a profile view of the doll head or similar article from the opposite side.

I claim:

The ornamental design for a doll head or similar article, substantially as shown.

EDGAR BERGEN.
